UNITED STATES PATENT OFFICE

JOY B. SCHMITT, OF TOLEDO, OHIO, ASSIGNOR TO THE DE VILBISS COMPANY, OF
TOLEDO, OHIO, A CORPORATION OF OHIO

SWITCH

Application filed May 19, 1927. Serial No. 192,505.

This invention relates to a switch adapted to be used for controlling all or a portion of an electric circuit, and constructed with special reference to its use in connection with portable electric appliances.

The object of the invention is to provide a switch of this type which is of simple, practical and durable construction, which is reliable in its operation, and which may be easily assembled or installed. In its preferred construction, the switch box or housing includes two members through which the conductor lines pass, one of these members being rotatable step by step successively to on or off position.

The specific construction of the invention in its preferred embodiment, together with the advantages resulting therefrom, will be more particularly explained in connection with the accompanying drawing illustrating the same. In the drawing:

Figure 1 is a longitudinal section through the axis of the switch.

Fig. 2 is a transverse section taken on the line 2—2 of Fig. 1.

Fig. 3 is a transverse section taken on the line 3—3 of Fig. 1.

Fig. 4 is a view partly in elevation and partly in section showing the relatively stationary member to which the conductor terminals are connected.

Fig. 5 is a detail perspective view of one of the stationary contact members.

Fig. 6 is a detail perspective view of the rotary bridge piece.

Referring in detail to the drawing, the switch constituting the subject matter of the invention comprises a cylindrical shell 7, which may be of metal, and within which is a relatively stationary switch block 8 of insulating material. This block is provided on its periphery with a longitudinal groove or keyway 9 adapted to receive a lug 10 formed on the inner face of the shell 7. The block 8 is formed centrally with a hub

11 which projects outwardly beyond the shell 7 and is provided with a central passageway 12 through which pass the conductor members 13 and 14. One of these conductor members, as 14, is cut and the ends thus formed connected to terminal posts 15 in the block 8.

Arcuate metallic plates 16 are secured to the face of the block 8 at opposite sides of its center and are electrically connected to the respective posts 15. The end of each plate 16 is formed at its outer edge with a lip 17 having a tongue 18 extending inwardly at an oblique angle within a recess 19 formed within the outer portion of the block 8. The face of the block 8 is enclosed by a cover 20 of insulating material which fits tightly within the rim of the shell 7 and which is provided centrally with a hole 21 through which the conductors 13 and 14 may pass. The periphery of the cover 20 is formed with a flange 22 which seats against the rim of the block 8 and the cover is dished outwardly so as to provide a suitable space for the arcuate plates 16 and the posts 15, to which the ends of the conductor 14 are connected.

A sleeve 23, also of insulating material, is rotatably mounted on the hub 11 and is formed at its inner end with a ratchet 24. A metallic bridge piece 25 is carried by the ratchet 24 and is in the shape of a flat ring, having radial lugs 26 terminating in laterally turned contact pieces 27, adapted to fit over the outer surfaces of certain teeth on the ratchet 24.

The block 8 has a peripheral flange 28 which extends between the contact pieces 27 and the shell 7 and has an opening just large enough to insert the ratchet 24 therethrough when the switch is being assembled. The shell 7 is formed with an inturned flange 29 which fits around the sleeve 23 and, in conjunction with the cover 20, holds the several parts of the switch in assembled

relation. An insulating washer 30 separates the ratchet 24 and contact pieces carried thereby from the flange 29. A knurled head 31 fits over the outer portion of the hub 11 and has a threaded connection with the sleeve 23.

In assembling the various parts of the switch, the arcuate plates 16 are permanently secured to the face of the block 8. The bridge piece 25 is placed against the face of the ratchet 24 with the contact pieces 27 against the corresponding teeth of the ratchet and the ratchet and sleeve 23 are then seated upon the hub 11 against the face of the block 8. The washer 30 and the shell 7 are then successively placed in position and the head 31 is then screwed upon the end of the sleeve 23 so that the parts of the switch thus assembled cannot become separated. The dished cover 20 fits into the end of the shell 7 and may be firmly held therein by friction.

In order to install the switch, it is only necessary to remove the cover 20, and after the conductors 13 and 14 have been inserted through the passageway 12 and opening 21, one of the conductors may be cut and its ends secured to the binding screws 15, after which the cover 20 may be replaced.

The bridge piece 25 may have any suitable number of contact pieces 27, while the number of teeth on the ratchet 24 should be double the number of such contact pieces. In the present embodiment, there are four contact pieces 27 and eight ratchet teeth. When the ratchet 24 is rotated step by step by means of the knurled head 31, the oppositely disposed tongues 18 will ride along the edge of the ratchet. These tongues are resilient and will in one position engage opposite contact members 27 to close the circuit and will in the next position engage intervening teeth of the ratchet to break the circuit.

It is obvious that this switch may be interposed in a conductor line at any point along the length thereof. It may be made comparatively small and light. It is especially adapted to be used on flexible wires which are connected to a portable electric appliance. The hub 11 is an integral part of the switch block 8, and it remains relatively stationary while the sleeve 23 and ratchet 24, together with the head 31 are rotated to switch the current on or off, thus protecting the conductor wires 13 and 14 against injury.

While I have shown and described in considerable detail the preferred form of the invention, it is obvious that the construction of the same may be considerably modified without any material departure from the salient features of the invention, as expressed in the claims, and without sacrificing any of its advantages.

What I claim is:

1. A switch comprising a block of insulating material having a hub projecting from one face thereof, a member mounted for rotation on said hub but held against axial movement with respect to said block, peripheral ratchet teeth on said member projecting in a plane perpendicular to the axis of rotation, a bridge piece held on said member and formed with contacts overlying certain of said teeth, co-operating contacts carried by said block and resiliently held against said member in the path of said first mentioned contacts, whereby to be electrically connected through said bridge piece, or disconnected, by the relative rotation of said member with respect to the block, a separable housing enclosing said block and said ratchet member and keyed to the block, and means extending outside the housing for effecting rotation of the ratchet member.

2. A switch comprising a block of insulating material formed with a hub projecting from one face thereof, said block and hub having a central opening through which the conductor wires may pass, a sleeve of insulating material rotatably mounted on said hub and formed at its inner end with a wheel having peripheral ratchet teeth projecting in a plane perpendicular to its axis, a bridge piece in the form of a ring circumscribing said hub between the block and said wheel and formed with contacts overlying certain of said teeth, said contacts serving to hold the bridge piece for rotation with the wheel, binding posts carried by said block, conductor members connected to said binding posts and having contacts overlying the rim of said wheel and resiliently held against the periphery thereof, whereby to engage the contacts on said bridge piece or disengage the same, as the wheel is rotated, and means for rotating said wheel at will.

3. A switch comprising two members of insulating material, one having a hub on which the other is rotatably mounted, said members having opposed flat faces perpendicular to the axis of rotation, means holding said members against relative axial movement, one of said members having peripheral ratchet teeth, a bridge piece held between said opposed faces, and formed with contacts overlying the sloping faces of certain of said teeth and serving to hold the bridge piece against circumferential movement with respect to said teeth, binding posts on the other of said members, contacts connected with said binding posts and resiliently held against said teeth to be connected by said bridge piece at certain periods in the rotation of said members.

4. A switch comprising two members of insulating material, one having a hub on which the other is rotatably mounted, one

of said members being formed with ratchet teeth, a separate bridge piece formed with contacts overlying certain of said teeth and held in position on the toothed member solely by engagement with said teeth and with the other member, contacts secured to said last mentioned member and alternately engageable and disengageable by the contacts on the bridge piece and upon relative rotation of the two members, and a separable housing holding said two members in assembled relation.

In testimony whereof I have hereunto signed my name to this specification.
